UNITED STATES PATENT OFFICE.

EMANUEL RABER, OF CANTON, OHIO.

ELEVATOR.

SPECIFICATION forming part of Letters Patent No. 243,791, dated July 5, 1881.

Application filed February 3, 1881. (No model.)

To all whom it may concern:

Be it known that I, EMANUEL RABER, a citizen of the United States, residing at Canton, in the county of Stark and State of Ohio, have 5 invented certain new and useful Improvements in Elevators; and I do hereby declare the following to be a full, clear, and exact description of the invention, such as will enable others skilled in the art to which it appertains to 10 make and use the same, reference being had to the accompanying drawings, and to letters or figures of reference marked thereon, which form a part of this specification.

Figure 1 is an end view of the elevator. Fig. 15 2 is a longitudinal section on line $z-z$, Fig. 1. Fig. 3 shows a modified form of trigger.

A represent a beam on which the elevator is mounted. The beam is preferably arranged in the upper part of the barn.

20 B B are ribs which rest upon the upper side of the beam.

C C are downwardly-extending side pieces attached to the ribs B and arranged one on each side of the beam. Friction-rollers may 25 be substituted for the ribs B.

If necessary the upper parts of the frame may be joined by suitable girts, as indicated by dotted lines.

D is a bottom piece connecting the lower 30 edges of the parts C.

E is a pulley near one end of the bottom piece, D.

F is a pulley mounted in a block, G G', the latter having an eye or loop at the lower end 35 for attaching the load, and having at the upper end an eye for the insertion of a hook.

H is a rope attached at one end to the carriage and running under pulley F and over pulley E to the point where is applied the power 40 which elevates the material.

I I' is a hook mounted in the carriage, between the side pieces, C C. It is held in place by pins O and O', the hook being provided with a slot, i , for the pin O, and with a slot, 45 $i' i^2$, for the pin O'. The slot i' is concentric with the lower part of the slot i , and the slots i' and i^2 are in substantially the same straight line. If the hook be thrust upward until the pin O is in the lower part of the slot i , the hook 50 can then be turned on said pin as a center, the slot i' permitting the passage of the pin O'.

$i^3 i^4$ are notches or recesses in the upper edge of the hook, near its heel end.

J is a stop or trigger mounted in beam A. It may be supported either by a stationary pin 55 engaging with the trigger by means of a slot in the latter or supported by a pin fastened to the trigger and arranged to rest upon the top of the beam, as shown in dotted lines, Fig. 2.

The elevator-carriage may be reciprocated 60 on the beam A by means of one or more ropes.

When a load is suspended from eye G the pulley-block G G' will be kept vertical, and if the rope H be drawn in the direction of the arrow x it will thrust said block upward and 65 also thrust upward the hook I I' and the trigger J. The upward movement of these parts will be stopped when the pin O' is in the position indicated by the dotted lines, Fig. 2.

If the elevator-carriage be then moved in the direction of the arrow y , Fig. 2, the radial wall 70 of notch i^4 will engage with the side j of trigger J, and the hook I I' will be rotated sufficiently to cause the part I to enter the eye g of the pulley-block. After said point has entered said eye the corner i^5 , near the heel of 75 the hook, reaches the bottom of the trigger and passes the same, and the pulley-block and the load are then suspended upon the hook I I'. The load is carried in the direction of the arrow y to the desired point, and is then released from the fork or other holder. (Not shown.)

After the load is dropped the carriage is returned to the position shown in Fig. 2. While returning to said position the radial wall of 80 the notch i^3 strikes the opposite side, j' , of the trigger J, and the hook is turned into the position shown in said figure. The turning up of the hook releases the pulley-block, which is lowered for another load. When the trigger 85 and carriage are in the positions shown the carriage is prevented from being moved in the direction of arrow y until the hook I I' and the trigger J are elevated by the pulley-block.

The trigger may be made in the shape shown 90 in Fig. 3 and pivoted in a corresponding slot in the beam. In many respects a trigger of the latter construction is preferable to the one above described.

Again, instead of the described construction 95 of hook and pins, use may be made of side pieces having slots corresponding to the slots

i i' i^2 and of a hook having movable pins attached thereto. The operation of such a construction would be substantially the same as that described.

5 The bottom piece, D, has a throat, d , arranged to receive and guide the upper end of the pulley-block.

The frame-work of the carriage may be made of wood or of castor wrought metal, as desired.

10 What I claim is—

1. In an elevator, the hook I I', provided with the slots i i' i^2 , and notches i^3 i^4 , in com-

bination with the studs O O', substantially as set forth.

2. The combination, with the slotted and i^5 notched hook I I', of the vibrating trigger or latch J, substantially as set forth.

In testimony whereof I affix my signature in presence of two witnesses.

EMANUEL RABER.
